UNITED STATES PATENT OFFICE

PER K. FROLICH, OF ELIZABETH, NEW JERSEY, ASSIGNOR TO STANDARD OIL DEVELOPMENT COMPANY, A CORPORATION OF DELAWARE

METHOD FOR THE PRODUCTION OF NORMALLY LIQUID HYDROCARBONS FROM GASEOUS OR LOWER BOILING HYDROCARBON MATERIALS

Application filed March 24, 1930. Serial No. 438,650.

The present invention relates to an improved method for the production of normally liquid hydrocarbons from gaseous or lower boiling hydrocarbon materials and more specifically to a process for the production of liquid hydrocarbons boiling within the range suitable for commercial gasoline from gaseous or low boiling hydrocarbons. My process will be fully understood from the following description read in conjunction with the drawing which is a semi-diagrammatic side elevation partly in section of the preferred form of the apparatus.

Large quantities of low boiling hydrocarbons such as ethane, propane, butane and the like, occur in natural or refinery gases and at the present time are largely used for fuel, due to the fact that such hydrocarbons are either gaseous or boil at too low temperatures to be included in commercial gasolines. I have discovered a method by which such materials may be converted into higher boiling products admirably suited for use in internal combustion engines and for other uses for which products of the same boiling range may be used.

My process consists in a series of steps as follows: First the conversion of saturated materials such as ethane, propane and butane into olefins, which is accompanied by the liberation of free hydrogen. The second step comprises removal from this gaseous mixture of the free hydrogen and the third step comprises polymerization of hydrogen-free gas to form normally liquid hydrocarbons suitable for commercial motor fuel. Each of the said steps will be separately described. The first, or cracking step may be carried out in any desired manner, for example; merely by heating to a decomposition temperature say from approximately 600° to 1000° C. either with or without pressure and in the presence or absence of catalysts, preferably used in nonferrous tubes or ferrous metal tubes containing 8% of chromium or more. The preferred method, however, is that disclosed in the co-pending application Serial No. 360,000 of the present inventor with B. O. Boeckeler which was filed May 2, 1929. This process comprises dehydrogenation of hydrocar-

bons by the use of certain catalytic agents at temperatures within the approximate range of 450° C. to 700° C. with or without pressure. Metallic catalysts have been found satisfactory and the mixture of metallic oxides after reduction with methanol, hydrogen or hydrocarbon vapors or otherwise, are preferred although other types of dehydrogenation catalysts may be used. Catalysts containing zinc and another metal which has two or more valences are particularly desirable, such as 30 mol percent zinc, 70 mol percent of chromium or other proportions of the same elements, or zinc and molybdenum or tungsten, vanadium and the like. The rate of flow of the gases in this process is preferably very rapid, for example; above about two volumes of hydrocarbon vapor per minute per volume of reaction space and under such conditions it is observed that two or more atoms of hydrogen are removed from the hydrocarbon molecule with substantially no decomposition of the carbon structure, that is to say, substantially no hydrocarbons of fewer carbon atoms are produced.

This process may be used on pure hydrocarbons or mixtures of two or more hydrocarbons and diluent gases including hydrogen, nitrogen, methane or other gases may be used. In this way the highest yield of olefins and consequently the lowest yield of methane which forms as a waste product in the process is obtained.

The gas obtained from the first step of my process comprises a mixture of olefins, unreacted paraffinic hydrocarbons, and hydrogen. Removal of the major quantity of the free hydrogen comprises the second step and this may be accomplished in any desired manner, for example; by liquefaction and subsequent rectification, or by other physical means, but it is preferably accomplished by a process of preferential oxidation which is disclosed in the co-pending application Serial No. 438,651, entitled Process for purifying gases filed on March 24, 1930, by A. White and the present inventor.

In the operation of the preferential oxidation method the gas is mixed with air or other gases containing free oxygen in substantially

- equivalent quantities required for complete combustion of the free hydrogen. The mixture is then passed over a catalytic material at a temperature within the range of about 250 to 450° C. with or without pressure. Means are preferably provided for removing the heat caused by the combustion and this may be done by the use of small tubes or by the use of tubes provided with fins or other heat radiating elements, or in the case of larger tubes where relatively large volumes of gases are to be treated, internal cooling with steam or other suitable means may be used.
- 15 It has been found that copper shot or copper oxide is the most satisfactory catalytic material, but other materials such as lead, nickel, tin, bismuth or their oxides or equivalent metals whose oxides are readily reducible by hydrogen within the specified temperature range or mixtures of such substances may be used. When the metals are used it is usually preferable to use temperatures in the upper end of the range given, for example from 300 to 450° C. while if the oxides are used lower temperatures such as 200 to 350° C. are more satisfactory. It is of advantage to remove as large a proportion of the free hydrogen as can be readily caused to react without substantial combustion of the olefins and it may be reduced below 5% in the outlet mixture or even as low as 3% or 1%. It is desirable to purify the gases of sulphur compounds prior to the partial oxidation step since sulphurous impurities tend to poison the preferential oxidation catalyst. The purification step may be carried out prior to the cracking step or after the cracking step and may be accomplished either by a soda wash or by equivalent means.
- 40 The third or polymerization step may be carried out under atmospheric pressure or at higher pressures, for example; above 100 pounds per square inch, but preferably in the range from 300 to 1000 pounds per square inch. The temperature may vary considerably within the approximate limits of 500 to 900° C. and it has been found that with higher pressure it is generally desirable to use somewhat lower temperatures. The time of reaction may vary widely, for example, from less than 1 minute at higher temperatures to 25 or 30 minutes or longer at lower temperatures and contact materials may be used, preferably of a metallic character having a high heat conductivity in order to maintain uniform temperatures throughout the reaction chamber.
- 60 Using the present process, comprising the three steps described above, yields of 1 to 5 gallons of liquid products may be obtained per thousand cubic feet of propane or gases comprising, ethane, propane and butane. One half or more of the distillate is generally sufficiently low boiling for commercial gaso-

line and is ordinarily admirably suited for use in internal combustion engines by reason of its anti-detonation qualities. It may be used alone or may be blended with other materials available in petroleum refineries. The higher boiling material is of a tarry nature.

Referring to the drawing, 1 designates a gas blower or compressor, 2 a heat exchanger and 3 a cracking chamber. The condenser 4 serves for the removal of any normally liquid products formed during the cracking. The gases are then passed either through a desulfurizer 5 or through a by-pass line 6 to the hydrogen remover 7 to which air is admitted by means of compressor or blower 8 and manifold 9 while steam may be admitted through line 10. From the hydrogen remover the gases either pass through cooler 11 or through by-pass line 12 and, after compression by compressor 13 and passage through heat exchanger 14, they come into the polymerizing chamber 15 which is followed by heat exchanger 14, condenser 16 and liquid receiver 17. The final liquid products are removed through line 18 and the gases through line 19.

As an example of the operation of my process propane is passed through a tube of copper or other metal such as chrome steel or ceramic material heated to a temperature of about 800° C. The outgoing gas has the following composition:

	Per cent	100
C ₃ H ₆	13	100
C ₂ H ₄	26	
H ₂	30	
CH ₄ + C ₂ H ₆	31	

This gas is then mixed with 15% of its volume of oxygen and is passed over copper shot at a temperature of approximately 400° C. the outlet gas now has the following composition, after being cooled to separate moisture:

	Per cent	110
C ₃ H ₆	18	
C ₂ H ₄	37	
CH ₄ + C ₂ H ₆	45	

The gas is now compressed to a pressure of 600 pounds per square inch and passed through a chamber held at a temperature of 525° C. at a rate so as to give a reaction time of about 30 minutes. About 61% of the olefins react and a yield of 4.56 gallons of liquid material is obtained from 1000 cubic feet of the inlet propane. About 4.26 gallons or over 90% of the total product boils within the range from 30 to 225° C. and has a bromine number of 110. The material is light in color and after finishing in the ordinary methods well known in the petroleum industry is admirably suited for use in internal combustion engines, being equivalent in anti-detonation value to a naphtha from an ordinary sweet crude, such as Mid Conti-

uent crude, to which 80% of benzol has been added.

The entire series of steps may be carried out at atmospheric or higher pressures, say 5 100 pounds per square inch or if desired, one or more steps may be at low pressure, while the other or others are accomplished at higher pressure. It is particularly desirable to conduct the cracking steps at atmospheric pressure or below 100 pounds, scrub with alkali to remove sulphur, remove free hydrogen at 10 the same pressure and subsequently polymerize at pressures above 100 pounds.

My invention is not to be limited by any 15 theory of the mechanism of the reactions nor to any specific example which may have been given for purpose of illustration, but only by the following claims in which I wish to claim all novelty inherent in my invention.

20 I claim:

1. An improved process for producing valuable higher boiling hydrocarbons from lower boiling saturated hydrocarbons of more than one carbon atom, which comprises 25 the steps of converting such saturated hydrocarbons into unsaturates, removing the major quantity of free hydrogen and polymerizing the olefins to form higher boiling hydrocarbons.

30 2. An improved process for converting low molecular paraffinic hydrocarbons containing more than one carbon atom into higher molecular weight hydrocarbons comprising 35 converting the paraffins to olefins and free hydrogen by the action of heat, removing the major quantity of free hydrogen by partial combustion and polymerizing the olefin product in absence of substantial quantities of free hydrogen.

40 3. An improved process for obtaining normally liquid hydrocarbons from gaseous hydrocarbons heavier than methane comprising the steps of converting a substantial part of the gaseous paraffins into olefins and hydrogen by application of heat at a decomposition 45 temperature, removing the major quantity of free hydrogen by partial combustion in the presence of a suitable catalytic agent and polymerizing the olefins in absence of 50 substantial quantities of hydrogen.

4. Process according to claim 3 in which the paraffins are converted into olefins by passage, at a temperature in excess of about 450° C. over a suitable dehydrogenation 55 catalyst.

5. Process according to claim 3 in which the paraffins are converted largely to olefins by passage at a temperature between 450 and 700° C. over reduced metal oxides.

60 6. Process according to claim 3 in which the mixture comprising olefins and hydrogen is mixed with a gas containing free oxygen and passed over a catalyst containing a metal whose oxide is readily reducible by hydrogen 65 while at a temperature from 200 to 350° C.

under conditions adjusted for preferential combustion of the free hydrogen.

7. Process according to claim 3 in which the gas mixture comprising olefins and hydrogen is mixed with a sufficient quantity of oxygen to combine with the free hydrogen and such mixture is passed over a catalyst comprising copper at a temperature between about 300 to 450° C. whereby the hydrogen is preferentially burned. 70 75

8. Process according to claim 3 in which the free hydrogen is preferentially burned under conditions adjusted so as to leave a gas mixture containing not over 5% of free hydrogen. 80

9. Process according to claim 3 in which the olefin mixture is heated so as to leave not more than 5% of free hydrogen and the resulting mixture is polymerized at temperatures from 500 to 900° C. 85

10. Process according to claim 3 in which the gas containing less than 3% of free hydrogen is polymerized under pressure at temperatures from 500 to 900° C. in a zone of substantially uniform temperatures. 90

11. Process according to claim 3 in which the gas containing not more than 3% of free hydrogen is polymerized under pressure in excess of 300 pounds per square inch. 95

12. Process according to claim 3 in which the olefin containing gas substantially free of hydrogen is polymerized by digestion under pressure in excess of 300 pounds per square inch for a period varying inversely with temperature. 100

13. An improved process for obtaining valuable hydrocarbon liquids suitable for motor fuel from hydrocarbon gases rich in a constituent heavier than methane comprising partially dehydrogenating the gases by 105 heat at temperature above 450° C. removing major quantity of free hydrogen by partial combustion with oxygen by passage over a catalyst containing copper, at a temperature between about 200 to 450° C. whereby 110 the outlet gas contains less than 3% of free hydrogen, polymerizing the olefins by digestion from a prolonged period at 500 to 900° C. under pressure above 300 pounds per square 115 inch and cooling and condensing normally liquid constituents.
